UNITED STATES PATENT OFFICE.

WILLIAM W. DINGEE, OF RACINE, WISCONSIN, ASSIGNOR TO THE J. I. CASE THRESHING MACHINE COMPANY, OF SAME PLACE.

GOVERNOR.

SPECIFICATION forming part of Letters Patent No. 615,144, dated November 29, 1898.

Application filed August 8, 1898. Serial No. 688,102. (No model.)

To all whom it may concern:

Be it known that I, WILLIAM W. DINGEE, a resident of Racine, Racine county, Wisconsin, have invented certain new and useful 5 Improvements in Governors, of which I do declare the following to be a full, clear, and exact description, reference being had to the accompanying drawings, forming a part of this specification.

10 The present invention has relation more particularly to that class of governors commonly known as "centrifugal" governors, in which spring-controlled weighted arms are employed.

15 The object of the invention is to provide improved means whereby the tension of the controlling-spring may be conveniently regulated from the outer side of the governor and without the necessity of its removal from the 20 shaft.

The invention consists in the novel features of construction hereinafter described, illustrated in the accompanying drawings, and particularly pointed out in the claims at the 25 end of this specification.

20 The present invention is shown as applied to governors especially designed for controlling the feed-carrier of a threshing-machine; but while the invention is especially adapted 30 for such a governor it may be advantageously employed in other situations.

Figure 1 is a view in side elevation of a portion of a threshing-machine having my improved governor applied thereto. Fig. 2 is a 35 view in side elevation of the same portion of a threshing-machine, but from the opposite side. Fig. 3 is a view in vertical section on line 3 3 of Fig. 4. Fig. 4 is a view in central vertical section through Fig. 3. Fig. 5 is a 40 view in vertical cross-section on line 5 5 of Fig. 3.

Referring to Figs. 1 and 2 of the drawings, A designates the inner end portion of the carrier-frame of a threshing-machine, adjacent 45 which is journaled in suitable manner a shaft B, carrying at one end a gear-wheel b, with which meshes a pinion c, that is formed upon or attached to the member C of my improved governor. The member C is provided with 50 an annular friction - rim c', adapted to fit

within a belt-rim c² of the member C' of the governor, the rim c² serving to receive a belt D, that passes over a drive-pulley E, that is carried at the end of a shaft e, that passes from side to side of the machine, the opposite 55 end of the shaft e carrying a pulley F, to which motion is transmitted by a belt f in the usual manner. Upon the inner face of the member C' of the governor are formed the bosses c³, to which the arms G and G' 60 are pivotally connected by bolts g'. Each of the arms G and G' is weighted, and the short end g² of the arm G is connected by a rod H with the arm G' at a short distance from its pivot-bolt g'. Upon the rod H is 65 mounted a controlling-spring K. The lower end of this spring bears against an offset g⁴, formed at one side of the end g² of the arm G. The opposite end of the coil-spring H bears against a regulator M, which in the 70 preferred form of the invention consists of a rod having an eye at one end and having its opposite end bent at an angle to the eye m and provided with a threaded portion m' to receive an adjusting-nut m². As shown, the 75 outer member C' of the governor is formed with an offset chamber C⁴, within which the body of the rod M extends, and at the bottom of the chamber C⁴ is a bearing plate or washer m³, through which the rod M passes 80 and against which the adjusting-nut m² will bear.

The weighted arms G and G' are provided with the usual friction pads or blocks g⁵, adapted to bear against the inner face of the 85 friction-rim c' of the governor member C.

From the foregoing description it will be seen that when the separator of the threshing-machine reaches the desired speed the weighted arms G and G' will be thrown outward by centrifugal force until the friction pads or blocks g⁵ engage the rim c' of the governor member C, thereby causing this member to revolve and through the medium of the pinion c and gear-wheel b to impart motion to the shaft B, whereby the carrier will be driven. When it is desired to adjust the spring K in order to vary the force of the spring and so insure the actuation of the carrier at the proper time and speed, the oper- 90 95 100

ator will by means of the adjusting-nut m^2 move the regulator or adjuster M, so as to increase or diminish the tension of the spring K, as required. By extending the regulator 5 or adjuster M at one side of the governor it is manifest that the operator can without removal of parts give the desired tension to the spring K.

While I have described what I regard as 10 the preferred form of the invention, it is obvious that the precise details of construction above set out may be varied without departure from the spirit of the invention.

Having thus described my invention, what 15 I claim as new, and desire to secure by Letters Patent, is—

1. A governor of the kind described comprising two members one of which members is provided with a friction-rim and the other 20 of which members is provided with weighted arms and with a controlling-spring located between the members, in combination with an adjuster for said spring extending through the side wall of one of said members at a point 25 below their rims.

2. In a governor of the kind described, the

combination with the member C having a friction-rim c' and with the member C' having a belt-rim and having the weighted arms provided with the friction pads or blocks g^5 and 30 with a controlling-spring, of an adjuster-rod M engaging said controlling-spring and extending through the side wall of the member C' below the belt-rim and a nut whereby the adjuster M may be shifted.

3. In a governor of the kind described, the combination with the member C provided with the friction-rim c' of the member C' provided with the weighted arms G and G' having friction-blocks g^5 , a rod II connecting said weighted arms G and G', a coiled spring K upon said rod II, said member C' being provided with an offset chamber C^1 , and an adjuster-rod M having an eye m encircling the rod II and movable thereon, a plate or washer m^3 through 45 which said rod M passes and an adjusting-nut m^2 for said rod M.

WILLIAM W. DINGEE.
